UNITED STATES PATENT OFFICE

ROBERT R. WEBB, OF LOS ANGELES, CALIFORNIA, ASSIGNOR TO CHARLES R. HADLEY COMPANY, OF LOS ANGELES, CALIFORNIA, A CORPORATION OF CALIFORNIA

LOOSE-LEAF FILE

Application filed December 1, 1930. Serial No. 499,150.

This invention relates to loose-leaf files of the type useful, for example, for holding meter-reading slips and like papers.

In filing meter-reading slips, it is often desired to place some of the slips in different angular positions relative to others of the slips. One position of the slips may indicate meters not yet read, another position may indicate meters read and another position may indicate a paid bill while still a fourth position may indicate an unpaid bill. Accordingly, a very important object of this invention is to make provision for retaining the slips in different angular positions with respect to one another.

Another important object is to provide a guide that can be readily thrown into guiding position or into a retracted position.

Other objects and advantages will appear in the subjoined detailed description.

The accompanying drawings illustrate the invention.

Figure 1 is an edge view of a file constructed in accordance with the provisions of this invention, slips being shown in the file. The covers are shown raised in dotted lines.

Figure 2 is a plan view of Figure 1, some of the slips being turned to different positions than in Figure 1.

Figure 3 is an enlarged vertical section on the line indicated by 3-3, Figure 1.

Figure 4 is an enlarged horizontal section on the line indicated by 4-4, Figure 2.

Figure 5 is a plan view of another form of file embodying the invention, the cover and the clamping device being omitted.

Figure 6 is a fragmental vertical section on the line indicated by 6-6, Figure 5.

Referring to the drawings, there is provided a base plate 6 and a cover, said cover comprising openable cover members 7 connected with a median cover or clamping strip 8 to which the cover members 7 are hinged, in a manner well understood in this art. Fixed in the base plate 6 is a post 9 which projects through a circular orifice 10 in the clamping bar 8.

The clamping strip 8 is provided with a clamping device, indicated in general by the character 11, whereby the clamping strip 8

may be locked in any desired position on the post 9. Though the clamping device 11 may be of any desired construction, I have shown one that has been described in detail in my co-pending application Serial No. 453,204, filed May 17, 1930. Briefly, the clamping device 11 is constructed as follows: The wall of the orifice 10 is formed by a metal bushing 12 which is secured in the clamping member 8. At its upper end the bushing 12 is crimped over a cover plate 13 which is provided with a central orifice 14 to accommodate a sleeve 15 through which the post 9 projects. The sleeve 15 is normally held downwardly in the bushing by a coil spring 16 that surrounds the sleeve between the cover plate 13 and an external shoulder 17 on the sleeve.

The sleeve 15 carries a number of balls 18 that are accommodated in radial orifices 19 in the sleeve 15. The bore of the bushing 12 is tapered, expanding upwardly so as to wedge the balls 18 inwardly against the post 9, thus clamping the clamping strip 8 on the post. To release the clamping strip 8 so that it may be slid up or down on the post, the operator will pull the sleeve 15 upwardly against the pressure of the spring, thereby moving the balls 18 into the larger bore portion of the bushing 12.

Eccentric of the post 9, there is movably connected with the base plate 6, a U-shaped slip guide 20, the side arms 21 of which are at opposite side edges of the base plate 6. The guide 20 is hinged or pivoted to the base plate in any suitable manner and, in the present instance, the base plate 6 is provided with a transversely extending channel 22 in which the horizontal middle portion 23 of the member 20 is rotatably mounted. In this instance a portion 24 of the base plate 6 is bent downwardly so as to form the channel 22. In other words, the portion 24 constitutes a bearing for the portion of shaft 23 of the member 20. The shaft 23 has flat faces 25, 26 at an angle to one another for selective engagement by a flat spring 27 which extends across the channel 22.

The spring 27 passes through slots 28 in the bearing 24 just beneath the under face of the base plate and the base plate is crimped down-

wardly to form projections or shoulders 29 at the ends of the spring 27 so as to prevent said spring moving endwise, thus insuring against said spring becoming displaced from the base plate.

5 The invention described above operates as follows: When it is desired to place slips on the post 9, the clamping device 11 will be released and the cover removed and the slip 10 will then be placed on the post in a manner well understood in this art. When it is desired to examine any of the slips on the file, the cover member or members 7 may be raised to the position indicated in dotted lines in 15 Figure 1. It will be seen that the slips may be turned into any desired position and that when turned so as to project laterally from beneath the cover, as in Figure 2, the slips rest against the guide arms 21, thereby keeping the edges of said slips in alignment. When it is desired to turn the slips so as to 20 occupy a position between the arms 21, said arms will be swung downwardly to the dotted position shown in Figure 1. The slip that it is desired to turn into this position will then be turned and the arms 21 again raised to 25 their vertical positions, thus confining some of the slips between the arms 21.

In this instance, the post 9 is provided near 30 its upper end with an annular groove 30 which, when the clamping device is raised sufficiently, will be engaged by the balls 18, thus to more securely hold the clamping strip 8 in a raised position. When the balls 18 35 engage in the groove 30, the cover may be readily turned into any desired position.

In the present instance the faces 25, 26 of 40 the shaft 23 are at a right-angle to one another so as to yieldingly hold the member 20 in either one of two positions at right-angles to one another, one of the positions being when the arms 21 are vertical and the other being when said arms are horizontal.

The foregoing is a description of the form 45 of invention illustrated in Figures 1 to 4 inclusive. Now describing the form of the invention illustrated in Figures 5 and 6, the elements that functionally correspond with those hereinbefore described are indicated by 50 the same reference characters with the addition of the suffix "a". As will be seen, the principal difference of this form of this invention over that previously described is that the slip guide 20^a is of sectional construction, 55 each section being L-shaped by reason of the shaft being divided in the middle at 31 so as to form shaft sections 23^a to each of which is connected one of the arms.

Since the two sections of the slip guide operate independently, two springs 27^a are provided and these are secured at one end by rivets 29^a to the base plate 6^a. The operation of this form of invention is the same as previously described for that shown in Figures 1 to 4 excepting that with this form either

one of the arms 21^a may be swung down into horizontal position while the other arm remains in vertical position to function as a guide for the slips as they are turned into position where they lie between the arms 21^a 70 when both of said arms are in raised position.

I claim:

1. A loose-leaf file comprising a base plate, a post projecting up from the base plate, and a guide hinged to the base plate and provided with arms at opposite edges of the base plate. 75

2. A loose-leaf file comprising a base plate, a post projecting up from the base plate, a guide hinged to the base plate and provided with arms at opposite edges of the base plate, and means yieldingly holding the guide in 80 different positions of adjustment.

3. A loose-leaf file comprising a base plate, a post projecting up from the base plate, a guide hinged to the base plate and provided with arms at opposite edges of the base plate, the guide being U-shaped and the intermediate portion of the guide being provided with a flat face, and a flat spring extending across 85 the intermediate portion and engaging the flat face when the guide is turned to bring the flat face uppermost. 90

4. A loose-leaf file comprising a base plate provided with a channel, a post projecting up from the base plate, a U-shaped guide having its intermediate portion in the channel, the base plate being provided with slots opening into the channel, and a flat spring beneath the base plate projecting through the slots 100 and having its under face engaging said intermediate portion. 95

5. A loose-leaf file comprising a base plate provided with a channel, a post projecting up from the base plate, a U-shaped guide having its intermediate portion in the channel, the base plate being provided with slots opening into the channel, and a flat spring beneath the base plate projecting through the slots, said intermediate portion having a flat 105 face to engage the under face of the spring when the U-shaped member is appropriately turned. 110

6. A loose-leaf file comprising a base plate provided with a channel, a post projecting up from the base plate, a U-shaped guide having its intermediate portion in the channel, the base plate being provided with slots opening into the channel, a flat spring beneath the base plate projecting through the slots 115 and having its under face engaging said intermediate portion, and projections from the under face of the base plate engaging the spring to prevent endwise displacement of the spring. 120

7. A loose-leaf file comprising a base plate, a post projecting up from the base plate, and a guide hinged to the base plate and provided with an arm adjacent to one edge of the base plate. 125

8. A loose-leaf file comprising a base plate, a post projecting up from the base plate, a guide hinged to the base plate and provided with an arm adjacent to one edge of the base plate, and means yieldingly holding the guide in different positions of adjustment.

5
9. A loose-leaf file comprising a base plate, a post projecting up from the base plate, a cover slidably mounted on the post, and a guide hinged to the base plate and provided with an arm adjacent to one edge of the base plate, said guide movable into position to hold the arm upright adjacent to one edge of the cover.

10
15 10. A loose-leaf file comprising a base plate, a post projecting up from the base plate, a guide hingedly engaged in the base plate and provided with an arm adjacent to one edge of the base plate, the hinge portion 20 of said guide provided with a flat face, and a flat spring extending beneath the base plate and across the flat face.

25
11. A loose-leaf file comprising a base plate, a post projected up from the base plate, and a plurality of guides each independently hinged to the base plate, and each provided with an arm, said arms being adjacent to opposite edges of the base plate.

30
12. A loose-leaf file comprising a base plate provided with a channel, a post projecting up from the base plate, L-shaped guides mounted to turn in the channel, the base plate being provided with slots opening into the channel, and flat springs beneath the base 35 plate projecting through the slots one for each guide and having their underfaces engaging the associated guides to yieldingly hold said guides against turning.

Signed at Los Angeles, California, this
